UNITED STATES PATENT OFFICE

JOSEPH B. CLAY, OF CEDAR FALLS, IOWA, ASSIGNOR TO CLAY EQUIPMENT CORPORATION, OF CEDAR FALLS, IOWA

COMBINATION VENTILATOR AND SMOKE PIPE

Application filed May 26, 1930. Serial No. 455,623.

My invention relates to improvements in combination ventilators and smoke pipes, and the object of my improvement is to supply a perfected combination of this class and of 5 an inexpensive, simple and effective nature.

Another object of my improvements is to provide means for inducing a suction within the upper part of a building with which the device is in direct communication, as also 10 in the various parts of the device itself to thus more quickly and thoroughly clear out vitiated air from the building and vent smoke from a smoke pipe, than could be the case with ordinary appliances of this character.

Another object of my improvements is to incorporate with the combination device means for preventing a down draft therethrough at any time, whether in the ventilator 15 or the smoke-pipe parts thereof.

Another object of my improvements is to supply means for adjustably governing the outlets of the ventilator as may be indicated for differing conditions of its use.

These objects I have successfully accomplished in actual practice by the means which are hereinafter described and claimed, and which are illustrated in the accompanying drawing, in which Fig. 1 is a central vertical section of my improved combination of 20 ventilator and smoke-pipe for a building or other structure, and Fig. 2 is a horizontal section thereof taken on the broken line 2—2 of said Fig. 1 looking downwardly.

My invention is not restricted to the precise construction and arrangement of parts herein shown and described, nor to the various details thereof, as the same may be modified or rearranged in various particulars without departing from the spirit and scope 35 of my invention, one practical embodiment of which has been herein illustrated and described without attempting to show all of the various forms and modifications in which my invention might be embodied.

My device is particularly appropriate to houses or buildings for animals or fowls, but may be used in any description of building or other structure to which it may be applicable.

The device comprises an open ended hollow 40 member 1, cylindrical as shown or otherwise

shaped, and which may have the pair of spaced inclined outwardly directed flanges 3 and 4 which may be made integral therewith, or of parts united in any convenient manner thereto, as by having the inner edges of the 55 flanges inserted within circumferential grooves 2 and secured therein to receive the inner terminations of matched roof boards 6 with a flashing plate 5 or otherwise, as the above feature is not claimed herein, being re- 60 served for and shown specifically in a co-pending application for patent.

At suitable intervals around the upper end of the member 1 are secured the lower parts 7 of standards whose parts immediately above 65 said member are crimped at 8 for a purpose to be described, and the standards above said crimps have secured thereto and depending centrally therebetween a sleeve 16 to receive and fit the upper end of a smoke-pipe 16^a 70 shown in both figures. The upper portion 15 of the sleeve 16 is flared outwardly and fastened rigidly at its circumferential margin to said standards and is of a diameter wider than the member 1 and spaced therefrom. 75 Another sleeve 13 is mounted for vertical adjustments in the upper portion of said member 1 and has its upper edge flared outwardly conically at 14, said edge having recesses 19 80 at spaced intervals equal in number to the standards 7, said recesses when the sleeve is partially rotated loosely receiving the crimped parts 8 of the standards, so that then the sleeve may be moved up or down by means of a depending handle bar 18 and 17 extending into the building below. As there are several sets of crimps 8, the sleeve 13 may be moved to adjustingly seat the flared margins 14 within the crimps after the sleeve has been 85 so rotated at the desired height, to thus more or less close the interspace of the inverted frustum 15 and the upper edge of said member 1 to thus vary the ventilator discharge outlet as may be necessary, or to completely close it.

The upper parts of the standards are continued upwardly beyond the conical deflector 15 a short distance, then bent horizontally and radially outwardly at 10, and have a hollow cone 11 secured centrally thereon. Far- 90 95 100

ther outwardly, the standard terminations 9 are bent at a right angle downwardly and have fastened thereon a vertical open ended cylindrical member 12 concentric with and 5 extending above the member 1 and also above the lower portion of the upper cone 11.

As before stated, the vertically adjustable and rotatable sleeve member 13 is manually operable from below to vary the area of the 10 discharging interspace of the member 1 and the inverted frustal top part 15 of the smoke-pipe receiving sleeve 16. This feature renders the appliance convenient for use on buildings of different character or dimensions, in the regulation of the ventilating discharge current of air rising from below when heated, the vitiated air escaping from within 15 the outer member 12, but the conical top element 11 being of greater diameter than the said discharge vent, prevents down drafts entering either said regulated interspace or the smoke-pipe members 15 and 16 and the smoke-pipe.

A horizontal current of air crossing the upper part of the device and the open upper end 25 of the circumferential member 12, will induce a suction in the latter, also in the ventilator member 13 and the smoke-pipe terminal 15 and 16, which will aid in their discharge, respectively of the vitiated air in the building 30 and the gaseous products of combustion of a heater therein. Rising currents of air without will, when entering the member 12 from below, be largely prevented from entering the smoke-pipe or the ventilator discharge opening, by reason of the superposed flaring parts 35 of the element 15, the cone 11 above, and also the flaring marginal parts of the sleeve 13 at 14.

40 A special use and convenience is afforded in that the inverted frustal margin 15 of the smoke-pipe sleeve 16 projects outwardly far enough beyond the ventilator member 1 so that sparks from the smoke-pipe cannot fall 45 back into the member 1 and into the building below.

Having described my invention, what I claim as new, and desire to secure by Letters Patent, is:

50 1. A device of the character described, comprising in combination, a hollow open-ended ventilator member in communication with a building, a wider superposed upwardly flared deflector with depending sleeve 55 spaced from said member concentrically, and rotatable means including a flared element whose flared part is parallel with the flared part of said deflector, for vertical adjustments of said sleeve either varying or closing 60 the interspace between them.

65 2. A device of the character described, comprising in combination, a hollow open-ended ventilator member in communication with a building, a wider superposed upwardly flared deflector with depending sleeve sup-

ported and spaced relative to said member concentrically, outwardly flared and downwardly sleeved means for adjustably either varying or closing the interspace of said member and deflector, and a downwardly 70 concaved cap wider than and supported in spaced relation above said deflector, and a cylindrical hollow member concentrically supported around the cap and said flared deflector.

75 3. A device of the character described, comprising in combination, a hollow open-ended ventilator member in communication with a building, a hollow open-ended sleeve within and spaced from the ventilator member concentrically to receive an end of a smokepipe and having at the top an outwardly flared margin in the shape of an inverted frustum wider than the ventilator member and spaced therefrom, a downwardly concaved cap supported above and spaced from said flared member concentrically and wider than it and said ventilator member, a hollow cylinder rotatably fitting within the upper part of said ventilator member and having a flaring top parallel with the flared margin of said sleeve and alined therewith, adjusting means for said cylinder to variably space it from the flaring margin of said frustum, and a hollow open-ended enclosure member concentrically spaced from and around the interspaces of said ventilator member, and said cap.

80 4. A device of the character described, comprising in combination, a hollow open-ended ventilator member in communication with a building, a smoke-pipe sleeve having a part depending centrally into said member and having an outwardly flared upper margin above and wider than the upper end of 85 said member, standards fixed on the outer wall of said ventilator member upon which the flared part of said sleeve is fixed, the intermediate portions of the standards being 90 provided with horizontally alined cross corrugations, a hollow rotatable member depending within said ventilator member from the top and having a top outwardly flared margin seated within alined corrugations of 95 said standards, said margin having circumferentially spaced recesses to release it from said standards to allow longitudinal adjustments thereof when rotated and then elevated or lowered relatively thereto.

100 In testimony whereof I affix my signature. 105
JOSEPH B. CLAY.
